UNITED STATES PATENT OFFICE

164,450

MINIATURE ILLUMINABLE CHURCH

Frederick W. Rosenkranz and Helen M.
Rosenkranz, Westwood, N. J.

Application August 29, 1950, Serial No. 11,984

Term of patent 14 years

(Cl. D29—1)

To all whom it may concern:

Be it known that we, Frederick W. Rosenkranz and Helen M. Rosenkranz, both citizens of the United States and both residents in the Borough of Westwood, county of Bergen, and State of New Jersey, whose post-office address is 11 Bergen Street, in said Westwood, have invented a new, original, and ornamental Design for a Miniature Illuminable Church, of which the following is a specification, reference being had to the accompanying drawings, which form a part hereof.

Figure 1 is a perspective view of a miniature illuminable church, showing our new design.

Figure 2 is an elevational view of one side of our church.

Figure 3 is a front elevation of our church.

Light reflecting crystals are applied to several portions of the church and base.

The side of the church not illustrated is de-

signed similarly to that shown. The back of our church is plain.

We claim:

The ornamental design for a miniature illuminable church, as shown and described.

FREDERICK W. ROSENKRAZ.
HELEN M. ROSENKRAZ.
